UNITED STATES PATENT OFFICE.

BENJAMIN F. SINGER, OF LANCASTER, PENNSYLVANIA.

TURBINE ENGINE.

Application filed December 4, 1923. Serial No. 678,440.

To all whom it may concern:

Be it known that I, BENJAMIN F. SINGER, a citizen of the United States, residing at Lancaster, in the county of Lancaster and 5 State of Pennsylvania, have invented certain new and useful Improvements in Turbine Engines, of which the following is a specification.

This invention relates to improvements in 10 turbine engines, and the object in the present instance is to provide an engine of the turbine class in which a plurality of jets of steam, water or other fluid are directed to opposite sides of a rotatable member rotating 15 on a horizontal axis.

The object of the invention is to provide a turbine that will be properly balanced at all times and I accomplish this by means of these oppositely directed fluid jets and a 20 series of pockets or vanes on each vertical side of the rotatable member, which pockets or vanes are alternately arranged as between one side and the other.

The invention contemplates a simple 25 structure comprising a rotatable member suitably mounted in a casing and supported by a suitable standard, the rotatable member being exposed and adapted to transmit power through the medium of a belt or 30 otherwise, as desired.

The invention is more fully described in the following specification and clearly illustrated in the accompanying drawing, in which:—

35 Figure 1 is a side elevational view of my device.

Figure 2 is a plan view thereof.

Figure 3 is a side elevational view of the 40 turbine with the casing removed, showing the pockets.

Figure 4 is a sectional view through 4—4 of Figure 3.

Figure 5 shows in detail, one of the 45 pockets.

50 The turbine engine embodying the invention comprises a casing 1 having its upper side portions formed to provide casing heads 2 between which heads is mounted the rotor of the turbine, which is indicated in general by the numeral 3. Said rotor comprises a flat-sided circular web 4 and a cylindrical body 5 peripherally surrounding the web. The rotor further comprises two annular pocket members 6, one arranged at each side 55 of the web 4 of the rotor. These pocket

members will presently be more specifically described.

Inside the casing heads, 2, and interposed between them and the pocket members 6 of the rotor, are located discs 7, forming closures for the pockets of the rotor, and these discs are each provided with a plurality of coiled springs 8 which bear between the discs and the respective casing heads to insure a relatively close fit as between the 60 discs and the faces of the pocket members.

Each pocket member 6 is provided upon one face with a series of spaced bosses 9 providing between them the pockets which are indicated by the numeral 6^a, and the pocket 70 members are held for rotation with the rotor 3. This rotation is insured through the medium of a series of spring backed studs 10, the springs 10^a for which are seated in the pocket members and the studs engaging 75 sockets 11 in the web 4 of the rotor.

The casing heads 2 are each provided with inlet and exhaust openings 14—15 and the inlets are, as usual, provided with suitable fluid jet nozzles, directed at such an angle 80 that the motive fluid will impinge on the resisting wall of each pocket as the rotor rotates.

In order to close the outer and inner sides 85 of the pockets 6^a, concentric outer and inner rings 16 and 17 respectively are fitted to each pocket member in the manner clearly shown in Figures 3 and 4 of the drawings, the inner edges of these rings or, in other words, the edges which are presented toward the 90 center of the rotor, engaging against the face of the annular body 6 of the respective pocket member, and the opposite or outer edges of the rings being engaged by the face of the respective plate 7.

Having thus described my invention, I 95 claim:

1. In a turbine engine, the combination of a support comprising two opposed casing members, and a rotatable member mounted 100 on the support within the casing, for rotation, said rotatable member having a series of pockets on each opposed vertical face, the pockets on one side being alternately arranged with relation to the pockets on the 105 opposite side, discs located between the casing and the rotatable member, and springs interposed between the casing and the discs, said casing having inlet and outlet openings, and a fluid supply jet in each of the inlets. 110

2. In a turbine engine, a support, a casing comprising two opposite portions, and a rotatable member mounted for rotation between said two portions, said rotatable member comprising a central body having a plurality of indentations in its opposed faces, a pair of members seated against the said opposite faces of the central member, and spring backed studs carried by said pair of members and adapted to engage said indentations, a pair of discs forming closures for the open sides of the pockets, springs interposed between the casing portions and said discs, inlet and exhaust openings in the casing portions, and fluid jets for the inlets.

3. In a turbine engine, spaced, fixed casing heads, a rotor rotatably supported between the heads and comprising a cylindrical body and a circular web within the same between the opposite sides thereof, a pair of concentric rings arranged at each side of the web within the circumference of the body and between the web and the respective casing heads, an annular pocket member arranged between the rings of each pair and having pockets presented toward the respective casing heads and closed at their inner and outer sides by the inner and outer rings respectively, means connecting the members with the web of the rotor for rotation therewith, motive fluid delivery means opening through each casing head, and exhaust conducting means likewise opening through each head.

4. In a turbine engine, spaced, fixed casing heads, a rotor rotatably supported be-

tween the heads and comprising a cylindrical body and a circular web within the same between the opposite sides thereof, a pocket member arranged at each side of the web of the rotor and comprising an annular body disposed against the respective side of the rotor web and connected therewith for rotation with the rotor, bosses upon the outwardly presented side of the said body arranged in spaced relation to provide between them pockets into which the motive fluid is to be injected, a pair of concentric rings associated with each pocket member and receiving between them said bosses whereby to close the inner and outer sides of the pockets, the edges of the rings next adjacent the web of the rotor engaging against said outwardly presented face of the body of the pocket member, and the other edges of the rings being flush with the outer surfaces of the bosses, circular discs arranged one between the inner side of each casing head and bearing against the last mentioned edges of the said rings and the said surfaces of the bosses, means holding the said discs stationary with respect to the casing heads and yieldably in engagement with the said edges of the rings and the said surfaces of the bosses, means for delivering motive fluid through each casing head and the respective disc to be injected into the pockets and effect rotation of the rotor, and an exhaust opening through each head of the casing.

In testimony whereof I affix my signature.

In testimony whereof I affix my signature.

BENJAMIN F. SINGER.
